UNITED STATES PATENT OFFICE.

ROBERT L. NUNN, OF CHICAGO, ILLINOIS.

CINDER-ARRESTER.

1,179,746.

Specification of Letters Patent. Patented Apr. 18, 1916.

Application filed May 25, 1915. Serial No. 30,437.

To all whom it may concern:

Be it known that I, ROBERT L. NUNN, a citizen of the United States, residing at Chicago, in the county of Cook and State of Illinois, have invented new and useful Improvements in Cinder-Arresters, of which the following is a specification.

The invention relates to cinder arresters, and more particularly to the class of cinder escape attachments for locomotives.

10 The primary object of the invention is the provision of a cinder escape wherein all cinders on leaving the smoke stack of a locomotive will be trapped, and thereafter conveyed beneath the boiler of said locomotive for the deposit of said cinders onto the bed of a track, thus obviating the possibility of such cinders and sparks flying through the air rearwardly of the train when traveling or at a standstill.

20 Another object of the invention is the provision of a cinder escape wherein the cinders from the smoke stack are arrested prior to the deposit on the bed of the track, the cinders also being cooled before the discharge thereof onto the track bed.

30 A further object of the invention is the provision of a cinder escape which is simple in construction, novel in form, reliable and efficient in operation, and inexpensive in manufacture.

With these and other objects in view, the invention consists in the construction, combination and arrangement of parts as will be hereinafter fully described, illustrated in the accompanying drawings, and pointed out in the claim hereunto appended.

35 In the drawings:—Figure 1 is a side elevation of a locomotive, showing the cinder escape attachment constructed in accordance with the invention applied thereto. Fig. 2 is a front elevation of the same. Fig. 3 is a vertical longitudinal sectional view. Fig. 4 is a perspective view of the baffle cone support. Fig. 5 is a sectional view on the line 5—5 of Fig. 3.

40 Similar reference characters indicate corresponding parts throughout the several views in the drawings.

45 Referring to the drawings in detail, A designates generally a locomotive, which is of any ordinary well-known construction, having the usual smoke stack B, through which the smoke and cinders from the firebox are discharged in the usual manner, and suitably supported upon this locomotive

is the cinder escape attachment hereinafter fully described.

The cinder escape attachment comprises a cylindrical drum 10, preferably made from sheet metal, and is arranged concentrically about the smoke stack B, the drum being of greater height than the said smoke stack and is fixed to the boiler of the locomotive in any desirable manner. This drum 10 is 65 designed to serve as a trap for all cinders and sparks emitted from the smoke stack B of the locomotive, the cinders and sparks being arrested therein in a manner presently described.

70 Arranged within the smoke stack B is an adjustable support comprising a central collar 11, an adjustable ring 12 concentric thereto, and adjustable spokes 13 which are joined to the collar 11 and ring 12 respectively in any suitable manner, the said spokes being arranged radially from the collar toward the ring. The adjustability of the support permits it to be mounted within different sizes of smoke stacks. 80 Fitted within the collar 11 is the apex 14 of an inverted conical shaped baffle head or cap 15 which is adapted to deflect the cinders and sparks from the smoke stack B laterally against the wall of the drum 10 so that said cinders and sparks will drop into the same and be prevented from discharging through the free end or open mouth of the drum, the circumferential wider end of the head or cap 15 being of 85 greater size than the circumference of the mouth of the smoke stack B so as to properly deflect the cinders and sparks leaving the latter into the drum. Connected to the larger end of the head or cap 15 at the periphery thereof are brace arms 16, the same being arranged radially at equidistances apart and are secured to the wall of the drum so as to hold the head or cap rigid and in proper position within the drum.

90 At the forward or front side of the drum 10 is a horizontally directed elongated opening 17, the same being covered by means of a wire mesh screen 18, and through which is admitted cold air to the interior of the drum 10 for the cooling of the cinders or sparks delivered thereto.

105 Communicating with the drum 10 at diametrically opposite points thereof are rearwardly inclined conveyer tubes or pipes 19, the same being disposed at opposite sides of the boiler of the locomotive A and are con-

nected to a Y union 20 which is mounted centrally in the top of a cylinder 21 which is located beneath the boiler and forwardly of the fire box of the locomotive A, the cylinder being supported in such position in any suitable manner, and through these tubes or pipes 19 communication between the drum 10 and cylinder 21 is had so that the cinders from the said drum will be conveyed through the tubes 19 into the cylinder for a purpose presently described.

Arranged within the cylinder 21 is a spiral way 22 to feed the cinders from the top of the cylinder 21 to and into a delivery spout 23 leading from the lower end of the said cylinder 21 in a direction rearwardly of the locomotive, the discharge end of the spout being disposed at the desired elevation above the bed 24 of the track 25 on which the locomotive A travels so that the cinders will be deposited from the cylinder 21 onto the track bed 24 through the spout 23 between the rails of the track.

In the use of the cinder escape it will be clearly apparent that the cinders and sparks will be arrested after leaving the smoke stack B of the locomotive A, and thereafter cooled prior to the delivery of the same from the escape onto the bed 24 between the rails of the track 25, and in this manner the said cinders or sparks will be prevented from flying through the air rearwardly of the locomotive.

Copies of this patent may be obtained for five cents each, by addressing the "Commissioner of Patents, Washington, D. C."

From the foregoing it is thought that the construction and manner of operation of the device will be clearly understood, and therefore a more extended explanation has been omitted.

What is claimed is:—

A cinder escape for locomotives comprising a cylindrical drum of a greater size than and adapted to be concentrically secured about the smoke stack of the locomotive and having a wire screened aperture in the front thereof near the lower end of the same, a spider supported within the stack, an inverted substantially conical shaped head carried by the support and having its wider end disposed above the outer end of the stack, braces extending from the wider end of the head to the drum, a cylinder arranged beneath the boiler of the locomotive rearwardly with respect to the stack, a conveyer pipe leading from the drum near its lower end and opening through the top of the cylinder, a spiral baffle within the cylinder, and a discharge spout leading from the bottom of the cylinder and having its free end directed rearwardly of the locomotive.

In testimony whereof I affix my signature in presence of two witnesses.

ROBERT L. NUNN.
